INVENTOR

Marie F. Robertson

BY

M. J. Cuswell

ATTORNEY

UNITED STATES PATENT OFFICE.

MARIE F. ROBERTSON, OF NEW YORK, N. Y.

SILENCER FOR TYPEWRITING MACHINES.

Application filed December 15, 1923. Serial No. 680,881.

To all whom it may concern:

Be it known that I, MARIE F. ROBERTSON, a citizen of the United States, and a resident of New York, in the county of New York 5 and State of New York, have invented certain new and useful Improvements in a Silencer for Typewriting Machines, of which the following is a full, clear, and exact specification.

10 This invention relates more particularly to a class of devices adapted to be used in conjunction with typewriting machines.

My invention has for its object primarily to provide a device or silencer designed to be employed for muffling the sound produced by the parts of typewriting machines when operated, in order to overcome the annoyance to listeners resulting from the noise especially where a number of the machines 20 are synchronously operated in a single room or compartment, and which is of a form adapted to be removably applied to the machine to allow of being made and sold independently of the typewriting apparatus as 25 well as permitting the device to be made in various sizes and shapes for use upon different types of typewriting machines. The invention consists essentially of a flat flexible body of sound muffling material, preferably 30 felt, and the body may be substantially rectangular or other appropriate shape of a size to permit of being removably disposed for covering the exterior of the walls of the frame of a typewriting machine exclusive 35 of the parts of the machine supporting the finger keys. The body may be divided into flexibly jointed rear wall, side wall and front wall sections having suitable cut-outs 40 for accommodating the parts of the machine protruding beyond the exterior of the frame to allow the device to snugly fit the body proper of the machine for serving to obstruct the passage of the waves of sound produced when the machine is operated.

45 A further object of the invention is to provide a silencer of a simple, efficient and durable form which may be folded into a compact parcel when not in use.

With these and other objects in view, the 50 invention will be hereinafter more fully explained with reference to the accompanying drawing forming a part of this specification in which similar characters of reference indicate corresponding parts in all the views, 55 and will then be pointed out in the claims at the end of the description.

In the drawing, Figure 1 is a perspective view of a typewriting machine with one form of silencer embodying my invention applied thereto. 60

Fig. 2 is a plan view of the silencer when in unfolded position for covering the frame of a typewriting machine, and

Fig. 3 is a perspective view of the silencer when in folded position for covering the 65 frame of a typewriting machine.

The device or silencer has a body 10 which may be made of any appropriate sound muffling flexible material, though I prefer to make the body of a sheet or strip of felt of a thickness adapted to obstruct the passage 70 of sound waves. The body may be substantially rectangular, as indicated, or of other suitable shape as well as being of an appropriate size to embrace the exterior of the rear wall 11, side walls 12, 13 and front wall 14 of the body, as 15 of a typewriting machine 16 which may be of a well known form having the top 17 of its frame overhanging the 75 walls of the body as well as having the protruding part 18 of the frame which supports the finger keys, as 19.

The form of the body 10 of the silencer illustrated is divided into a rear wall section 20, side wall sections 21, 22 and front 80 wall sections 23, 24. These sections of the body are flexibly jointed together, at 25, 26, 27, 28, and the joints may be provided by stitching or otherwise hingedly fastening the opposed ends of the sections together. 85

The rear section 20 is substantially rectangular, and this section is of a size so that its upper edge closely fits under the overhanging rear edge of the top 17 of the 90 frame of the body of the machine. In the upper edge of the rear wall section 20 may be a cut-out, as 29, for accommodating a part of the machine, not shown, which protrudes beyond the rear wall 11 of the body 15 of the frame of the machine. Each of 95

the side wall sections 21, 22 of the flexible body 10 is also approximately rectangular as well as being of a size so that both sections closely fit under the overhanging side edges of the top of the frame of the body of 100 the machine, and in the upper edge of each of the side wall sections 21, 22 may be spaced cut-outs, as 30, 31, for accommodating the parts of the machine, as 32, protruding beyond the frame of the machine. Each 110

of the front wall sections 23, 24 of the flexible body 10 are of combined shapes and

sizes for covering the front wall of the body 15 of the frame of the machine, and in the upper free corner of each of the front wall sections may be cut-out 33 of a curvature conforming to the arched portions 24 in the upper part of the front wall of the frame of the machine. Also in the free end of each of the front wall sections 23, 24 below the cut-out 33 may be a cut-out 35 for accommodating the protruding part, as 36, of the machine when the front wall sections are in covering positions on the front wall of the frame of the machine. Through the front wall section 23 at its juncture with the side wall section 21 may be an opening or cut-out, as 37, for accommodating still another part, as 38, protruding from the machine. The body 10 is thereby made of a size to snugly fit in surrounding position the front wall, side walls and rear wall of the body proper of the machine for serving to muffle the sound of its parts when operated without interfering with the operation of the machine in the usual manner.

In the foregoing description, I have embodied the preferred form of my invention, but I do not wish to be understood as limiting myself thereto, as I am aware that modifications may be made therein without departing from the principle or sacrificing any of the advantages of this invention, therefore, I reserve to myself the right to make such changes as fairly fall within the scope thereof.

Having thus described my invention, I claim as new and desire to secure by Letters Patent:—

1. A silencer for typewriting machines, having a flat flexible body of sound muffling material including flexibly jointed rear wall and side wall sections for being removably disposed to cover the rear wall and side walls of the frame of the machine exclusive of the parts of the frame supporting the finger keys and each of said sections having cut-outs for accommodating parts of the machine protruding beyond the exterior of the frame.

2. A silencer for typewriting machines,

having a flat flexible body of sound muffling material including flexibly jointed rear wall, side wall and front wall sections for being removably disposed to cover the rear wall, side walls and front wall of the frame of the machine exclusive of the parts of the machine supporting the finger keys and each of said sections having cut-outs for accommodating parts of the machine protruding beyond the exterior of the frame.

3. A silencer for typewriting machines, comprising a substantially rectangular sheet of felt of relative thickness for obstructing the passage of waves of sound, said sheet divided into sections flexibly connected for being removably arranged to closely cover the rear wall and side walls under the overhanging upper edge of the frame of the machine exclusive of the parts of the frame supporting the finger keys.

4. A silencer for typewriting machines, comprising a substantially rectangular sheet of felt of relative thickness for obstructing the passage of waves of sound, said sheet divided into sections flexibly connected for being removably arranged to closely cover the rear wall, side walls and front wall under the overhanging upper edge of the frame of the machine exclusive of the parts of the frame supporting the finger keys.

5. A silencer for typewriting machines, comprising a substantially rectangular sheet of felt of relative thickness for obstructing the passage of waves of sound, said sheet divided into sections flexibly connected for being removably arranged to closely cover the rear wall, side walls and front wall under the overhanging upper edge of the frame of the machine exclusive of the parts of the frame supporting the finger keys and each of said sections having cut-outs for accommodating parts of the machine protruding beyond the exterior of the frame.

This specification signed and witnessed this 14th day of December, A. D. 1923.

MARIE F. ROBERTSON.
